PRINTING MECHANISM

Harold S. Labombarde, Nashua, N. H., assignor
to The International Paper Box Machine Company, Nashua, N. H., a corporation of Maine

Application January 19, 1935, Serial No. 2,560

6 Claims. (Cl. 101—177)

There are two types of rotary printing presses, the gripper press printing one sheet to a revolution or to two revolutions and the web press which may print any number of impressions per revolution. The objection to the web press is that the cylinder circumference must be in exact ratio to the number of images to be printed. This makes the web press non-flexible, that is to say, if said ratio is to be changed all the printing cylinders of the web press have to be changed. With my invention I may always use the same cylinder diameter but, because of using individual sheets, I may vary the space between sheets, it being understood that this space will vary depending on the length of the sheet. With the web press the plate cylinder has the plate all the way around while I may have a thin metal plate which does not cover the entire circumference of the plate cylinder. With the web press, as a practical matter, the space between images must be negligible because such space means a waste of paper when the printed portion is died from the rest of the web while with my invention the spaces between blanks may be varied depending on the size of the printed blank and whether one, two or more images are printed per revolution, it being understood that I may have, within limits, any desired number of images per revolution of the printing cylinder. I may have a removable plate around the printing cylinder and this removability permits a ready change from one plate to another. The space between the ends of the plate is not harmful because this space will correspond with the space between individual blanks. In the gripper press it is impossible to handle many odd-shaped blanks since the grippers contact only a portion of the blank, the remainder of the blank being out of control while the blank is carried around the cylinder. With my invention the blank is flat at all times during the printing and therefore is under the control of the printing surfaces, these being preferably the perfectly cylindrical surfaces of the blanket cylinder and the impression cylinder. As one illustration of my ability to handle odd shapes I refer to the double wrap drinking cup, the sheet in such being semi-circular. As another illustration I refer to small tin plates, especially irregularly-shaped tin plates, which may be very satisfactorily printed by my mechanism because of my offset printing and the fact that the tin plates do not need to be bent around a cylinder as they are at present.

The principal object of my invention is to provide a mechanism for printing a wide range of

blanks, for example, a single image covering practically the entire cylinder or a plurality of images on the surface of the cylinder may be used and moreover on my printing cylinder I may have a set of one or more images on the printing cylinder for printing one stream of blanks and another set of one or more images on the printing cylinder, spaced axially from the first set, for printing another stream of blanks and the latter stream may be different in shape, size and color from the first stream. 5

Another object of my invention is to provide mechanism for printing blanks and especially flexible individual blanks such as sheets of paper and to do this printing at a very high rate of 15 speed and without the use of grippers in the printing operation. When grippers are used in the printing operation a speed of two hundred blanks per minute is the highest practical speed obtainable while with my invention a speed of 20 four hundred even up to eight hundred per minute is entirely practical, the rate of printing depending on the number of imprints for each revolution of the printing cylinder.

An important feature of my invention is that 25 I provide offset printing, among other purposes, to eliminate make-ready and to provide the ability to print on rough surfaces.

Another important feature is a blanket cylinder having a perfectly true cylindrical surface, 30 this surface being particularly important because it takes part in the advance of the blank under perfect register and control.

Another feature is means for keeping the blank substantially horizontal as it leaves the printing 35 cylinder.

Another feature is means for stacking the printed blanks in substantially vertical position to prevent transfer of the printing from one blank to another and to provide a stack such that 40 blanks may be removed at any time as desired without stopping the machine and without marring the printing.

Another feature is the provision of means for giving the desired tilt to the stacked blanks. 45

Another feature is a printing cylinder having a plurality of sets of images, these sets being spaced apart axially of the cylinder.

Another feature is means for lifting the rear edge of a printed blank out of the way of the succeeding blank. 50

Other features will be pointed out below.

In the drawings:

Figure 1 is an elevation, partly in section, of a printing mechanism embodying my invention; 55

- Figure 2 is a plan of the same, but with some parts omitted;
- Figure 3 is a detail of the stacking mechanism on a larger scale;
- 5 Figure 4 is an end view looking from the line 4-4 of Figure 3;
- Figure 5 is a detail of the pin registering mechanism described below;
- 10 Figure 6 is a detail of the pin mechanism;
- Figure 7 is a perspective view showing the mechanism for driving the toothed member described below;
- Figure 8 is a detail of the stripper;
- 15 Figure 9 is an enlarged view of the mechanism for adjusting the cylinders, looking from the opposite side of Figure 1;
- Figure 10 is a sectional detail of the adjusting mechanism for the printing cylinder, the section being on line 10-10 of Figure 9;
- 20 Figure 11 is a sectional detail, on line 11-11 of Figure 9, of the register chain adjustment;
- Figure 12 is an enlarged detail of the mechanism for carrying the blank to the stacker;
- 25 Figure 13 is a plan of a portion of the gripping mechanism, on a larger scale;
- Figure 14 is an elevation of said portion of the gripping mechanism on a larger scale;
- 30 Figure 15 is a detail, on a larger scale, of a portion of the stacking mechanism;
- 35 Figures 16 and 17 are enlarged details of the registering mechanism;
- Figure 18 is a partial section, enlarged, on line 18-18 of Figure 2;
- Figure 19 is an end elevation, enlarged, looking in the direction of the arrows from line 19-19 of Figure 2;
- 40 Figure 20 is a diagrammatic plan showing a printing cylinder having two sets of images; and
- Figure 21 is a fragmentary view of a modification described below.
- The individual blanks to be printed are placed in hopper 1 from which they are fed, one by one, by a suitable feeding mechanism which, in the form shown, comprises a combing wheel 2, a cleaning brush 3 and a gate 4, these parts and the mechanism operating them being like those shown in my Patent No. 1,897,484 dated February 14, 1933. Two belts 5 and 6 carry each blank forward, belt 5 being driven by pulley 7 and belt 6 by pulley 8, these pulleys being driven by chain 9 which is driven by shaft 10, the latter being driven, through suitable gearing, by shaft 11, the parts being mounted in frames 11a and 11b.
- 55 As the blank is advanced by the belts it is held down on the belts by metal balls 16 in suitable cages 17 and is side-registered by vertical members or guides 18 and 19 which are mounted on cross rods 20 and 21 and held in the desired 60 adjusted position by wing nuts 22, 22' and 23 and 23'.
- As the blank nears the end of its travel on the belts its front edge is brought into engagement with abutments 24, 25, 26 and another, not shown, 65 which, in the form shown, are pins secured to chains 28 and 29. The speed of the belts is substantially greater than the speed of said abutments so as to hold the front edge of the blank firmly against the abutment.
- 70 The cages 17, the belts 5 and 6 and the chains 28 and 29 are all mounted on castings 30 and 31, the latter being mounted for transverse adjustment by screws 32.
- Chains 28 and 29 are driven by sprockets 33 75 and 34 fixed to shaft 10.

The impression cylinder 35 may be moved toward and from the printing cylinder 14 by a hand lever 36, which, when swung to the left, moves short arm 37 toward the left to move gear 38 and thereby move the eccentric bearing 39 to adjust the position of the impression cylinder.

After the edge of the blank has been registered against the moving abutments, such as 24, and before the abutments start their downward movement, the blank is engaged by two top rolls 10 40 and 41 which are mounted on shaft 42, to which is fixed gear 43, which, through idle gear 44, is driven by gear 45 fixed to shaft 46, which, by suitable gearing, is driven by main drive shaft 15. Shaft 46 is fixed to the blanket or printing cylinder 14. A bottom roll 47 is mounted on stud 48 which is fixed in casting 30 and another bottom roll is similarly fixed in casting 31. The top rolls and bottom rolls act to advance the blank after it has been accurately registered 20 against the abutments and before the latter start their downward movement. Rolls 51 and 52 are driven by suitable gearing from shaft 42 and act to advance the blank to position between printing cylinder 14 and impression cylinder 35.

The ink on cylinder 14 tends to lift the forward portion of the blank but this tendency is resisted by the teeth 53 fixed to shaft 54, the latter being driven at higher peripheral speed than that of the printing cylinder 14 by compound gearing 30 55, 56, 57 and 58. Said teeth engage the forward edge of the blank and throw it down so that the entire blank is substantially horizontal. To aid this throwing action I provide air holes from the centre of the hollow shaft 54 leading out to the periphery, the air being forced into the hollow shaft by a suitable pump.

To prevent the forward edge of the blank from bending down and following the impression cylinder, if, for example, the static electricity should 40 give a greater pull than the ink, I provide a doctor 59 which is pivoted at 60 and held in contact with the impression cylinder by spring 61.

When the blank leaves the cylinders 14 and 35 it is advanced on aprons 62 and 63, driven by suitable mechanism such as the sprockets 64 and 45 65 and the chain 66.

If a portion of the blank is unprinted the top pressure rolls 67 are positioned over the unprinted portion of the blank and keep the latter 50 in engagement with the apron, said rolls being pivoted and held down by springs 68.

If the blank has so much printing that the use of said pressure rolls might result in their engaging the printed portion, then I keep the blank 55 down on the aprons by the use of air engaging the top of the blank. This air is brought to proper position over the blank by air pipes 69 adjustably mounted on cross bar 70. The air is fed to the pipes by a suitable air pump.

The speed of the apron travel should be preferably the same as the surface speed of the printing cylinder.

When the blank is about to leave the aprons its forward edge enters between the jaws of grippers, each of which comprises a jaw 71 which is fixed with relation to the chain 72 and comprises a jaw 73 pivoted to jaw 71. Mounted on an extension of jaw 71 is spring finger 74 and I provide coiled spring 75 which tends to close jaws 71 and 70 73. When the chain carries the jaws upwardly into proximity to the forward edge of a blank spring finger 74 is bent to the position shown in Figure 12 and stationary cam surface 76 acts to open jaws 71 and 73 by engaging arm 77 which 78

has fixed connection with jaw 73, so that the forward edge of the blank is forced in between the jaws, it being understood that the speed of the aprons is preferably about twice the speed of travel of the chain. When the forward edge of the blank is between the jaws the pivoted arm 77 leaves the cam surface whereupon the coiled spring 75 forces the jaws into position to grip the forward edge of the blank. As the chain 10 now travels around an arc the spring finger acts to lift the blank, as shown in Figure 3, so that the rear edge will be lifted out of the path of the next advancing blank. The purpose of this is to permit the speed of the aprons to be much greater than the speed of the grippers without interference with the gripping action. When the gripping jaws carry the blank around the arc pivoted arm 77 is engaged by adjustable cam 78 and the jaws are opened to release the blank 20 which comes to rest on stripper 79 which is mounted on bar 80. Oscillator 81, sliding on rod 82 and driven by crank arm 83, fastened to gear 84, pushes the blank just released into the pile and on its backward stroke allows the blank to 25 drop from stripper 79 to bar 80 in which position the stripper acts to hold the blank in its substantially vertical stacked position and spaced from the next incoming blank.

If the blank is of thin and yielding material such, for example, as newspaper, the pile of blanks may buckle down and to overcome this, if it should occur, the entire mechanism which delivers from the aprons is pivoted about bushing 85, pivoted arms 86 being notched to engage 35 pin 87 so that the desired tilt may be given to the stacked blanks.

Sprocket 65 is fixed to shaft 88 carrying gear 89 which, through gear 90, drives gear 91 which, in turn, drives shaft 92, to which are fixed by 40 keys, with provision for sliding movement, sprockets 93 and 94 engaging chains 72. In order to take up any stretch of chains 72 I provide sprockets 95 which have studs 96 which may be adjustably located in slots 97 on the frame.

The chains 72 and their actuating mechanism are mounted on portion 98 of the frame of the stacker, which has screws, such as 99, the latter providing for transverse adjustment of said chains and actuating mechanism.

Ink for printing is distributed from fountains 100 through ductor rolls 101 to ordinary distributor rolls 102 and thence to plate cylinders 103 which in turn transfer the inked image or printed surface to the printing or blanket cylinder 14, the latter transferring the ink to the individual blank. The plate cylinders 103 may have two images as indicated in Figure 5, this permitting the printing of two blanks, if desired, for one revolution of the cylinders.

Stud 81^a (see Figure 8) provides an anchor for one end of spring 61 and the stud may be screwed into the frame at any suitable place.

In Figure 6 I have shown a portion of chain 28 having ordinary links 28^a, pivotally connected 65 to each other by block 28^b, into which is screwed pin 24 which consists of threaded stud 24^a and eccentric bushing 24^b. If one of the chains 28 should stretch relatively to the other the stud 24^a may be unscrewed to permit rotary adjustment of the bushing so that its rearward portion 70 will align with the pin of the corresponding chain at the other side of the machine so that the two pins will properly align the blank.

In Figure 9 the impression cylinder 35, which 75 is driven by gearing indicated in Figure 2 as 15^a,

15^b and 15^c, is fixed to shaft 11, the latter having fixed to it gear 35^a, which, through gear 35^b, drives gear 35^c fixed to shaft 10. On shaft 46 is fixed gear 46^a, as by screws and keys. Gear 46^a is clamped by screws 46^b to gear 45. Into gear 5 10 45 extends stud 46^c supporting pinion 46^d. When screws 46^b are loosened gear 46^a may be rotarily adjusted by turning 46^d with a suitable tool. Similar rotary adjustment may be provided for cylinders 103, 103.

In Figure 11 I show gear 35^c (shown in Figure 9) as fixed, as by pressing, to an extension of gear 35^d, the latter being driven, through intermediate pinion 35^e, by gear 35^f which is fixed to shaft 10. Nut 35^g clamps gear 35^c to handwheel 15 20 35^h and when loosened allows gear 35^c to be rotated for the purpose of turning shaft 10 to adjust sprockets 33 and 34 so that pins 24 and 25 may be adjusted with relation to the image on the printing cylinders.

In Figures 13 and 14 I show the grippers in a rotary position other than the positions shown in Figures 3 and 12, the open position of jaw 73 being indicated in Figure 14.

In Figure 15 I show a portion of the stacking 25 mechanism on a larger scale, the cam member 78 being adjusted by screw 78^a mounted to turn in block 78^b, the latter being suitably fixed on frame 98.

Frames 104 and 105 are pivoted to the frames 3^a 35^b and 11^a on brackets 106 and 107, said frames 104 and 105 being pivoted on the bearing bushings of shaft 92. Frames 98 and 98^a are held in alignment with brackets 104 and 105 by bar 108 and the whole unit, namely, elements 104, 105, 98 35 and 98^a and the mechanism carried by them, is 35^b swung by arms 86 to give the desired tilt to the stacked blanks.

In Figure 18 I show, enlarged, a portion of the structure of cylinders 14 and 103, it being understood that the cylinder covering 109 in Figure 18 is metal for cylinders 103 and a rubber blanket for cylinder 14. This covering is perforated near its edge at suitable intervals crosswise of the machine, the edge being held between plates 110 40 45 extending parallel with the axis of the cylinder, these plates having holes drilled to register with the perforations in the covering. Screws 111 hold the plates in position with said edge clamped between them. The edge of the covering at the 50 left of Figure 18 is similarly held between plates, which are clamped by screws 112, the latter entering shaft 113 which has pinned to it an angular portion 114 to receive a wrench for turning the shaft. Said angular portion is integral with 55 a ratchet wheel 115 whose teeth are engaged, as desired, by pawl 116 so that the shaft may be turned and held in the turned position by pawl 116, to keep the cylinder covering as tight as desired.

In Figure 21 I show a double blanket comprising not only the rubber covering 109 but also an inner rubber blanket 125 which acts as a cushion for the printing blanket or cover 109, this inner blanket acting to absorb the pressure created, for 65 example, by doubled over blanks or if two sheets were accidentally fed. If this pressure were not absorbed the blanket will be ruptured by such extraordinary pressure. The inner blanket is fastened at one end and floats at the other so 70 that it may accommodate itself to the stretch of the outer blanket.

In Figure 20 I show a blanket cylinder 14^a having a set of images 117 and a set of images 118, these sets being spaced apart axially of the 75

cylinder. A stream of blanks 119 may be fed on belts 120 and 121 corresponding to belts 5 and 6 and a different stream 122 may be fed on similar belts 123 and 124. Chain pins similar to 24 and 25 will be used and the two streams will be printed simultaneously between the blanket and impression cylinders.

An important advantage of my invention is that any given point on my registering chain will 10 complete one cycle of its travel in exactly the same time as is taken by a given point on the blanket cylinder circumference for a complete cycle of its travel, the result being that if the chain stretches one of the abutments may be 15 adjusted so that it will be located exactly halfway around the chain with relation to the other abutment. If the plates are inaccurate in the making and the images are not located exactly in the desired position adjustment of the pin abut- 20 ments will compensate for error in the plates.

A great advantage of my stripper which is the toothed member 53 is that if for example, the machine were stopped for even a short time, the ink on the blanket roll becomes tacky and when 25 the machine is started again the blank will stick to the blanket roll unless prevented by the stripper 53 or by the air through the air holes or by both. If not stripped the blank may be carried up and ruin the blanket and perhaps the ink rollers.

30 What I claim is:

1. In a high speed printing machine, the combination with an impression cylinder of a coacting blanket cylinder to receive one or more printing images extending in circumferential arrangement about the cylinder for printing a succession of individual blanks means for moving the respective blanks in a substantially straight line between said cylinders, each in timed registry with a printed image on the blanket cylinder, and 35 a positively actuated continuously rotating stripper means located close to the periphery of the blanket cylinder and beyond and above the point where the blanks are imprinted with said images and acting to engage the forward edge of the blank and force it downwardly so that the entire blank is substantially horizontal during the printing operation.

2. In a high speed printing machine, the combination with an impression cylinder of a coacting blanket cylinder to receive a plurality printing images extending in circumferential arrangement about the cylinder and spaced axially of said cylinder for printing a succession of individual flexible blanks, means for moving the respective blanks in a substantially straight horizontal line between said cylinders, each in timed registry with a printed image on the blanket cylinder, and a continuously rotating toothed stripper member located outside the blanket cylinder in close proximity to and above the delivery side thereof in position to engage and strip the blanks regardless of the timing of their delivery and acting to engage the forward edge of the blank and force it downwardly so that the entire blank is substantially horizontal during the printing operation.

3. A printing mechanism comprising an impression cylinder and a blanket cylinder to receive one or more circumferentially disposed

printing images for successively imprinting individual flexible blanks as they pass between said cylinders in a substantially straight horizontal line in timed registry with the images on the blanket cylinder, and a stripper comprising a continuously operating air flow element located adjacent to the blanket cylinder beyond and above the printing line and acting to detach the forward end of each blank being printed from adherence to the offset cylinder and to force it downwardly so that the entire blank is substantially horizontal during the printing thereof.

4. A printing mechanism comprising an impression cylinder and a blanket cylinder to receive one or more circumferentially disposed 15 printing images for successively imprinting individual flexible blanks as they pass between said cylinders in a substantially straight horizontal line in timed registry with the images on the blanket cylinder, and a stripper located adjacent 20 to the blanket cylinder beyond and above the printing line comprising a continuously rotating perforated toothed air flow element acting to detach the forward end of said blank being printed from adherence to the blanket cylinder and to force it downwardly so that the entire blank is substantially horizontal during and after the printing operation.

5. A high speed printing machine, adapted to print a wide variety of blanks, comprising a 25 blanket cylinder to receive a plurality of sets of circumferentially spaced images of differing size or shape, a cooperating impression cylinder, means for feeding a plurality of series of blanks in a straight line between said blanket and impression cylinders at a constant speed, means 30 cooperating with said feeding means to cause proper registration of the respective blanks with the complementary images of the respective sets, a positively actuated stripping means located adjacent to the blanket cylinder beyond and above the printing line and rotating at a greater peripheral speed than that of said offset cylinder, acting to detach the forward end of each blank being printed from adherence to the blanket 40 cylinder and to force it downwardly so that the entire blank is substantially horizontal during and after the printing thereof.

6. A high speed printing machine, adapted simultaneously to print a plurality of blanks, comprising a blanket cylinder to receive a plurality of circumferentially spaced sets of images in axially spaced relation, a cooperating impression cylinder, parallel feeding means for presenting a plurality of series of blanks in a straight line to the respective sets of circumferentially spaced images between said blanket and impression cylinders at a constant speed, and means 45 cooperating with respective feeding means to cause proper registration of the respective blanks with the complementary images and a positively rotated toothed stripping member located adjacent to the blanket cylinder and beyond and above the printing line acting to force the forward end of the blank downwardly so that the entire blank is substantially horizontal during and after the printing operation.
